UNITED STATES PATENT OFFICE.

JAMES HENRY RUSH, OF BOSTON, MASSACHUSETTS.

GUIDE-LUBRICATOR.

No. 884,957.

Specification of Letters Patent. Patented April 14, 1908.

Application filed September 21, 1907. Serial No. 393,946.

To all whom it may concern:

Be it known that I, JAMES HENRY RUSH, a citizen of the United States, and a resident of Boston, in the county of Suffolk and State 5 of Massachusetts, have invented new and useful Improvements in Guide-Lubricators, of which the following is a full, clear, and exact description.

This invention is an improvement in guide 10 lubricators, especially designed for elevators, and serving to automatically and effectually lubricate the guides or rails without waste, during the travel of the elevator car.

The object of the invention is to provide a 15 receptacle for holding a lubricant, as grease or graphite, which will admit of the guide passing thereto in contact with the lubricant, and in which the lubricant will tend to move toward the guide as it becomes exhausted.

Reference is to be had to the accompanying drawings forming a part of this specification, in which similar characters of reference indicate corresponding parts in all the views.

25 Figure 1 is a perspective view of a portion of the guide and cross-head of an elevator, showing one embodiment of my improvement applied thereto; Fig. 2 is a plan of the construction shown in Fig. 1; and Fig. 3 is a 30 perspective view showing my improved lubricator made as a separate part from the cross-head.

The lubricator comprises a hopper-shaped receptacle 5 which is preferably substantially 35 rectangular in cross-section, with the bottom thereof removed, and is provided with a vertical slot 6 formed in one side for the reception of the guide or rail of the elevator, as illustrated in Figs. 1 and 2.

40 The side of the receptacle which is constructed with the slot is upright, whereas the remaining three adjacent sides are downwardly and inwardly inclined, whereby the grease or graphite placed in the receptacle 45 will tend to move in the direction of the guide, as it becomes exhausted and sinks in the receptacle.

The width of the slot 6 and the open bottom of the receptacle is such, that the receptacle 50 will closely fit the rail or guide of the elevator and thus prevent undue application of the grease to the guide and avoid waste.

I have shown in Fig. 1 the receptacle formed as an integral part of the cross-head; this, however, may be modified by casting or 55 otherwise producing the receptacle as a separate part, as illustrated in Fig. 3, and thereafter bolting or otherwise rigidly securing it to the cross-head. For this purpose, as shown in Fig. 3, the receptacle is provided at 60 its bottom with an exteriorly arranged flange 7, the said flange surrounding the receptacle except at the slotted side thereof.

While the design of my improved lubricator as shown and described is my preferred 65 practical construction, it is obvious that minor changes may be resorted to without departing from the nature of my invention as defined in the annexed claims.

Having thus described my invention, I 70 claim as new and desire to secure by Letters Patent:

1. A guide lubricator comprising a hopper-shaped receptacle for holding the lubricant, having a slot in one side thereof for receiving 75 the guide of the elevator, whereby said guide passes into the receptacle in contact with the lubricant.

2. A guide lubricator comprising a receptacle for holding the lubricant, having the 80 bottom thereof open and provided with a vertical slotted side for receiving and substantially fitting the guide, whereby said guide is adapted to project into the receptacle in contact with the lubricant. 85

3. A guide lubricator comprising a receptacle of substantially rectangular cross-section for holding the lubricant, having the bottom thereof open and with three adjacent sides inclining inwardly and downwardly, the 90 other side of the receptacle being substantially vertically slotted for permitting said guide to project within the receptacle in contact with the lubricant.

In testimony whereof I have signed my 95 name to this specification in the presence of two subscribing witnesses.

JAMES HENRY RUSH.
